CLOSING PLATE FOR ELECTRIC METER SOCKET

Jack Moran, Muskogee, Boyd Steveson, Fort Gibson,
and William A. Reynolds, Oklahoma City, Okla., as
signors to M-R-S Inc., Fort Gibson, Okla.

Filed Aug. 14, 1969, Ser. No. 18,687

Term of patent 14 years

Int. Cl. D13—99
U.S. Cl. D26—1

FIG. 1

FIG. 2

FIG. 3

FIG. 1 is a front elevational view of a closing plate for an electric meter socket showing our new design;

FIG. 2 is a rear elevational view; and

FIG. 3 is a side elevational view.

We claim:

The ornamental design for a closing plate for electric meter socket, substantially as shown.
